UNITED STATES PATENT OFFICE.

HERMAN WEPPLER, OF COLUMBUS, MONTANA.

EMASCULATING TOOL.

Application filed May 22, 1924. Serial No. 715,146.

To all whom it may concern:

Be it known that I, HERMAN WEPPLER, a citizen of the United States, residing at Columbus, in the county of Stillwater and 5 State of Montana, have invented certain new and useful Improvements in an Emasculating Tool, of which the following is a specification.

This invention relates to new and useful 10 improvements in emasculating tools for removing the male genital glands of lambs.

Another important object of the invention 15 is to provide an emasculating tool of the above mentioned character, wherein the same includes cooperating cutter blades for slitting the scrotum, and a pair of cooperating gripping jaws for removing the testicles.

A further object of the invention is to 20 provide an emasculating tool of the above mentioned character, which is simple in construction, inexpensive, strong and durable and furthermore adapted for the purposes for which it is designed.

A further object is to provide an emasculating tool which is of such a construction 25 as to save considerable time and labor and rendering the removal of the testicles more sanitary.

Other objects and advantages of this in- 30 vention will become apparent during the course of the following description.

In the accompanying drawing forming 35 part of this specification and in which like numerals designate like parts throughout the same:

Figure 1 is a top plan view of my im- 40 proved invention.

Figure 2 is a side elevation thereof, and

Figure 3 is a fragmentary detail perspective view of one of the levers showing the blades and gripping jaw associated therewith.

In the drawing wherein for the purpose 45 of illustration is shown the preferred embodiment of my invention, the numerals 1 and 2 designate a pair of crossed levers which are pivoted intermediate their ends in the manner shown at 3 in the drawing. The inner ends of the levers are provided 50 with suitable handles 4 and 5 respectively, the portions of the levers 1 and 2 adjacent the pivotal connection 3 and disposed on the opposite side thereof on which the handles are formed are disposed downwardly as 55 shown at 6 and 7 respectively in the drawing.

The downwardly extending portions 6 and 7 terminate in the horizontally extending inwardly curved outer ends 8 and 9 respectively. The curved portions 8 and 9 terminate at their outer ends in the upwardly extending coacting gripping jaws 10 and 11 respectively and the inner opposed faces thereof are provided with cooperating teeth 12 and 13 respectively in the manner clearly 60 illustrated in the drawing. The purpose of the gripping jaws will hereinafter be more fully described.

The curved portions 8 and 9 of the outer 65 ends of the levers provide a means for securing a pair of cooperating cutter blades 14 and 15 respectively. The cutter blades are preferably of arcuate formation and have their arcuate edges extending substantially flush with the outer edges of the curved portions 8 and 9 and the blades are secured to the under sides of the curved portions by any suitable fastening means such as is shown at 16. The cutting edges of the cutter blades are illustrated at 17 in the drawing. 70

In use, the tool is operated by means of the handle portions 4 and 5 and when the cutter blades are open, the scrotum is held by a person so that the cutter blades may 75 engage the same and by operating the handle portions, the cutting edges 17 will slit the scrotum whereby access to the testicles may be had. The tool is then operated so that the gripping jaws 10 and 11 will engage 80 the testicles and by moving the handle portions inwardly, the teeth on the inner opposed edges of the gripping jaws will securely hold the testicles against accidental displacement from the gripping jaws and by 85 exerting a pull on the tool, the testicles may be easily and readily removed.

It will thus be seen from the foregoing 90 description, that an emasculating tool has been provided which will render the removal 100 of the male genital glands more sanitary than the methods now employed and the simplicity in which my device is constructed enables the same to be easily and efficiently operated. Furthermore, the provision of a 105 tool of the above mentioned character, may also be used as an ear marker.

While I have shown the preferred embodiment of my invention, it is to be understood 110 that various changes in the size, shape and arrangement of parts may be resorted to without departing from the spirit of the in-

vention and the scope of the appended claim.

Having thus described the invention, what is claimed is:—

- 5 An emasculating tool comprising a pair of pivoted cross levers, handles provided on the inner ends thereof, the outer ends of the levers being directed downwardly adjacent the pivotal connection and thence disposed horizontally and curved, and terminating in

a pair of upstanding cooperating gripping jaws, the inner opposed faces thereof being provided with gripping teeth, and blades provided with opposed straight cutting edge and outer arcuate edges curved concentric with and attached to the outer horizontally disposed and curved portions of the outer ends of the levers. 15

In testimony whereof I affix my signature.
HERMAN WEPPLER.
